UNITED STATES PATENT OFFICE.

FREDERICK BOESSER, OF PERTH, WESTERN AUSTRALIA, AUSTRALIA.

WASHER FOR DRINKING GLASSES AND VESSELS.

Application filed July 31, 1920. Serial No. 400,501.

To all whom it may concern:

Be it known that I, FREDERICK BOESSER, a subject of the King of Great Britain, residing at 679 Beaufort Street, Perth, Western

5 Australia, Commonwealth of Australia, have invented certain new and useful Improvements in Washers for Drinking Glasses and Vessels, of which the following is a specification.

10 This invention provides an hygienic appliance for washing drinking glasses and similar vessels as in a running stream of pure water, the glass being subjected to a number of water jets which are adapted to a strike and impinge in a tangential manner on and against the outside and inside surfaces of the vessel being washed and cause it to be rapidly rotated in a turbine manner during such washing action, with the result

15 that the outside and inside of said vessel are thoroughly washed and cleansed. The construction and use of the invention will be explained with the aid of the attached drawing which shows the appliance fitted in position

20 within a suitable cup-shaped chamber *y* in a counter or table as *x*. Referring to said drawing, *a* is the central vertical pipe having the outer branch pipes, as *b* and *c*, which are fitted with the upper and inwardly inclined extension pipes *b*¹ and *c*¹ provided with the removable caps *d* for cleaning out purposes. These extension pipes *b*¹ and *c*¹ have screw thread connection with said branch pipes *b* and *c* and may thereupon be

25 adjustably positioned at varying angles in respect of said branch pipes *b* and *c* in order to suit vessels of varying shapes and sizes. Small perforations are formed in the extension pipes *b*¹ and *c*¹ through which per-

30 forations water jets escape and strike downwardly on and against the outside of the inverted glass *f*, indicated by broken lines and assist in its rotation. The central pipe *a* is provided with a head *g* having preferably

35 four horizontally outstanding tubular stems *g*¹ formed with perforations through which water jets *j* escape for the washing of the inside of the glass *f*. The head *g* has an upper conical portion *k* which also has perforations through which water jets *m* whose spe-

cial purpose is to strike against and wash the inside bottom of the glass *f*, escape upwardly. Said inner jets *j* and *m* serve, in conjunction with the outer jets *e*, to rotate and wash the glass *f*. The head *g* terminates in a conical stem *n* which acts as a pivot for the freely rotatable skeleton frame *n*¹—said frame having at its lower end a collar *n*² encircling the pipe *a* to maintain said frame in upright position. The head of said frame is provided with a rubber cap *p* on which the glass *f* is supported in an inverted position while being washed and rotated by the water jets as already explained. Water under pressure is supplied to the vertical and branch pipes from supply pipe *r* having the turn off cock *r*¹ and spring controlled inlet valve *r*². The valve *r*² is operated by lever *s* pivoted at *s*¹ and the lever *s* is connected by a suitable wire or chain *t* to a foot pedal *t*. The auxiliary spring *s*² urges and quickly returns said lever *s* to its normal position and the inlet valve *r*² to closed position. The appliance is fitted and works within the well *y* mounted in the draining tray *y*¹ on which the washed glasses *y*² are placed and is provided with a waste water pipe *y*³.

To work the appliance: The pedal *t*¹ is depressed and through the chain *t* and lever *s* opens the inlet valve *r*² permitting jets of water *e*, *j* and *m* to escape from the perforations for the external and internal washing and rotation of the vessel *f*. When the pedal *t*¹ is released the spring *s*² returns it to the normal position and the inlet valve *r*² is closed. The vessel is then removed from the cap *p* and frame *n*¹ and placed upon the draining tray *y*¹.

What I claim as my invention and desire to secure by Letters Patent is:—

A washer for drinking glasses and the like, comprising a vertical water pipe having a conically pointed perforated head, perforated stems extending radially from said head, lateral branch pipes extending radially outward from said vertical pipe and then upwardly in spaced parallel relation to said vertical pipe, said branch pipes having inwardly inclined perforated and rotatably adjustable extensions, a skeleton glass-hold-

90

100

ing frame supported on said pointed head to hold a glass in inverted position and rotate about said head within said branch pipes, and a rubber cap on the upper end of said skeleton frame for cushioning the glass on said frame.

In testimony whereof I have hereunto set

my hand in presence of two subscribing witnesses.

FREDERICK BOESSER.
